**METHOD OF FORMING A LOCK KNOT
FOR COIL SPRINGS**

Martin Kaiser, 66 Spencer Ave., Toronto 3,
Ontario, Canada

Filed Apr. 13, 1964, Ser. No. 361,929
5 Claims. (Cl. 140—101)

This invention relates to a method of forming a lock knot on a coil spring knotting machine wherein a knotting pinion is used to form the free end of the coil spring about an adjacent winding to lock the end of the coil spring.

Conventional coil knotting machines utilize the method of forming the knot comprising the steps of securing the coil spring in position whereafter the free end of the coil spring is bent inwardly and coiled about the adjacent coil winding for approximately three turns. With properly adjusted machines a reasonably tight coil is produced which however has some tendency to slip on the adjacent winding whereby the end of the coil spring can become larger or smaller. This is a serious disadvantage since in the manufacture of furniture spring cushions, mattresses and the like it is desirable to have dimensional stability in the individual coil springs in order that a completed coil assembly will fall within specified dimensional limits.

The coiling of the knot about the adjacent winding is normally accomplished by means of a knotting pinion gear which is placed about the adjacent winding whereafter a spur on the gear picks up the tail end of the coil and winds it about the adjacent winding to form the knot. This gear however soon becomes worn and produces a loose knot which results in an unacceptable coil spring. Thus frequent replacing of the knotting pinion is required in order to produce even reasonably acceptable coil springs.

In the present invention however means are provided for forming a knot which is locked securely in position in a positive manner, whereby an acceptable coil spring is produced. It is therefore an object of the present invention to provide a method of forming a lock knot on a coil spring, whereby even with a slightly worn knotting pinion an acceptable knot can still be produced.

It is a further object of the present invention to provide a method of forming a lock knot on a coil spring wherein the knot is tensioned against restraining bends on the adjacent coil, thereby to ensure continuous positive attachment of the knot on the coil in order to ensure dimensional stability of the coil spring at all times.

In the present invention three bends are formed in the coil at the knot location, whereby the knot is restrained from movement along the adjacent coil thus the coil end is maintained at one constant diameter and further if desired the knot may be wound in an open manner whereafter it can be compressed and held thus by the bends in the adjacent coil winding, whereby the knot is under tension at all times.

Other objects and features of the invention will be apparent from the following detailed description and accompanying drawings in which like numerals refer to like parts throughout the various views.

In the drawings:

FIG. 1 is a front elevation of apparatus for carrying out the steps of the present invention;

FIG. 2 is a section along the line 2—2 of FIG. 1;

FIG. 3 is an elevation view of a portion of the apparatus as illustrated in FIG. 1 and shows the reverse side thereof;

FIG. 4 is a fragmentary view of a portion of the apparatus as illustrated in FIG. 1 taken in the direction of the arrow 4;

2

FIG. 5 is an end elevation of a knotting pinion for use with the present invention;

FIG. 6 is a side elevation of the knotting pinion as shown in FIG. 5;

5 FIG. 7 is a fragmentary view of a portion of the apparatus for use with the present invention and particularly illustrates means for providing the last bend in the coil;

FIG. 8 is a fragmentary view of a knot formed according to the present invention in an anti-clockwise direction;

10 FIG. 9 is a fragmentary view of a knot formed according to the present invention in a clockwise direction;

FIG. 10 shows the coil spring placed in the notch 42;

15 FIG. 11 shows the coil spring in place, in the knotting pinion in the slit 39, ready for the winding action;

FIG. 12 shows the pinion 36 ready to engage the wire 21 to start the winding;

20 FIG. 13 shows the coil spring 21 after the pinion 36 has wound the wire for one half turn;

FIG. 14 shows the coil spring 21 after one and a half turns; and

25 FIG. 15 shows the coil spring 21 after the full two and a half turns.

With reference to FIG. 1, FIG. 2, and FIG. 3 apparatus for carrying out the steps of the invention this apparatus being adaptable for use in widely used automotive spring coiling machines is illustrated and comprises a knotting machine indicated generally as 11 having a supporting base 12 onto which is secured a holding die 13 which is adapted to support a coil spring 14 thereon.

30 A gripper head 15 slidably supported in guide 16 and 17 is adapted for reciprocal movement toward and away from die 13 and as will be seen in FIG. 4 the head 15 is adapted to secure the coil spring 14 in two positions, in the upper position indicated as 18, the adjacent coil 19 (shown in phantom) is held, at the lower position indicated as 20, the tail end 21 of the coil spring 14 is held.

35 A rocking arm 22 supported on pin 23 is operated by a cam 24 on the cam shaft 25. The cam shaft 25 is operated from the mechanism of the coil knotting machine which 40 is conventional and well known in the art. The shaft 25 is suitably timed by providing the necessary gearing between the normal driving shaft within the coil knotting machine. An intermediate sliding member 26 is slidably positioned on the supports 27 and 28 and is operably connected to the rocking arm 22 and the gripper head 15 whereupon rotation of the cam 24 the gripper head 15 is caused to move into position against the die 13 to ensure the coil spring 14 as noted.

45 A cradle 29 is pivotally supported on a shaft 30 and 50 is adapted to pivot into an operable position by means of the cam 31 mounted on shaft 32. It should be noted that the shaft 32 is by suitable gearing connected in timing with the cam shaft 25 by well known and conventional means.

55 Cradle 29 has a driving gear 33 which is secured to the shaft 30 and rotates therewith and during the forming of a single knot on the coil gear 33 makes one revolution the position of start and stop being maintained by the pawl 34 dropping into a recess 35 on the hub of the gear 33.

60 Cradle 29 also rotatably supports a knotting pinion 36 which is illustrated in detail in FIGS. 5 and 6. Knotting pinion 36 comprises a body portion 37 provided with a conical inner surface indicated as 38 reading to a slot indicated as 39 at one end thereof. The bottom end of the slot 39 at the center of the pinion as indicated at 40 is adapted to be a comparatively close fit on the diameter of the wire of spring 14 whereby upon upward movement of the cradle 29 the wire of the spring 14 will be securely gripped by the knotting pinion 36. Pinion 36 is provided with a wire catching portion 41 which engages

with the tail end 21 of the spring 14 in the well known and conventional manner.

Cradle 29 is also provided with a notch on the side plate 42a at 42 whereby upon upward movement of the cradle 29 the tail end 21 is secured by the notch and bent inwardly towards the center of the coil spring 14 substantially at right angles to the adjacent coil 19.

A hammer 43 is slidably positioned in guides 44 and 45 and is operably connected with the cam 46 by means of the rocking arm 47 whereby upon rotation of the cam shaft 25 hammer 43 is caused to move inwardly. As shown in FIG. 7 upon the hammer 43 moving inwardly into position within the cone surface 38 of the knotting pinion 36 the end of the hammer 43 being provided with a small groove as indicated at 48 engages the adjacent coil 19 whereby a bend 54 is formed therein.

In use the present method is first to support the spring 14 onto the fixture 13 whereafter the gripper 15 is moved into position to secure the adjacent coil winding 19 and to secure the tail end 21 substantially as shown in FIG. 4. The cradle 29 is then caused to move upwardly whereby the tail end 21 engages on the notch 42 of the cradle and is bent substantially at right angles to the adjacent coil winding 19 and is brought into engagement with the projecting catching portion 41 of the knotting pinion 36, the adjacent winding 19 being positioned into the slot 39 that is located at a slight angle with direction of movement of cradle 29. As the cradle 29 moves upwardly the adjacent coil winding 19 is bent backwards towards the base of the coil spring 14 by means of the edge 49 of the knotting pinion 36 impinging thereon, thereby to form a first bend 50 as illustrated in FIG. 8 that shows a knot formed anti-clockwise about coil 19, knot 53 proceeding under coil 19 on the adjacent coil winding 19.

FIG. 9 shows a knot 53a formed in clockwise direction over coil spring 19a, knot 53a proceeding over coil 19a. The present invention is the only device that will produce such a clockwise knot.

Shaft 30 is then rotated to cause the knotting pinion 36 to rotate approximately one-half turn whereby the tail 21 is wrapped about the adjacent winding 19. The indentation of selective size indicated as 51 in FIG. 2 on the cam 31 allows the cradle 29 to move downwardly whereby the knotting pinion 36 bends the adjacent coil winding 19 away from the center of the coil thereby to form complete a second bend 52 as illustrated in FIG. 8 and at the same time make the base perfectly concentric. Hereafter the gear 33 causes the knotting pinion to rotate approximately two and one-half turns more whereby the completed knot as shown in FIG. 8 as 53 is formed upon knotting gear having rotated a full 3 turns. Before release of the coil spring 14 or before completion of the knot, the cam 46, operating through the arm 47, causes the hammer 43 to move forward and strike the adjacent winding 19 as shown in FIG. 7 to bend the winding toward the base of the coil spring 19 to form the third bend 54 as shown in FIG. 8.

From the foregoing it will be seen that the method of the present invention provides a knot which is securely held on the winding of the coil spring and that a substantially uniformly round spring is produced. The knot 53 as shown in FIG. 8 is held from movement by means of the bends 52 and 54 and the bend 50 ensures that the completed end coil will lie in a plane substantially at right angles to the axis of the coil spring 14.

A further improvement is provided in that the shaft 30 shown in FIG. 3 (supported on bearing supports 55 and 56) can move from side to side. To this end a cam face 57 is provided on the end of the shaft 30 and adapted to bear against a roller 58 mounted on a support 59. As winding of the knot 53 as shown in FIG. 8 progresses, the natural resilience in the material of the spring 14 will force the shaft against the roller 58. If desired a second cam 60 may also be placed at the opposite end of the shaft 30 whereby the movement of the shaft 30 will be independent

of the resilience of the spring material and that further the coil spacing of the knot 53 can be controlled. Thus in this manner the coil of the knot 53 may be wound in a close or open manner to begin with whereafter during 5 the end of the winding it may be compressed into a tighter coil whereby upon forming of third bend 54 the knot 53 will be held compressed. Also the knot 53 may be wound in an open manner whereafter completion of the knot, it can be compressed by suitable movement of the shaft 30 to form a tighter knot, whereafter the third bend 54 10 can be formed to secure the knot in the compressed condition, which may be formed before completion of the knot to accentuate compression thereon.

From the foregoing it will be seen that the method of 15 the present invention is first to form a bend in the adjacent coil winding whereafter the knot is partially formed on the winding and a second bend is provided to form a means for locking one end of the knot. Further winding of the knot either open to be compressed or closed 20 to be tightly wound on the adjacent winding is accomplished until approximately two and a half further turns have been completed. A third bend is then formed on the adjacent winding to securely lock the knot in position.

It will be further understood that although specific 25 embodiments of the invention have herein been described and illustrated, the invention also contemplates such variations as may fall within the scope of the appended claims.

The embodiments of this invention in which an exclusive property or privilege is claimed are defined as follows:

1. A method of forming a lock knot on a coil spring by means of a knotting pinion, said pinion having a radial slit extending from the center to the peripheral edge thereof; and means to control same and comprising the steps of: securing said coil spring at one end thereof and 35 leaving a tail end of said coil spring free; bending the tail of said coil inwards towards the center of said coil until said tail is substantially at right angles to the adjacent coil winding; moving said knotting pinion with said radial slit at a slight angle to the plane of the end coil of said coil 40 spring, into position about said adjacent winding backwards towards the base of said coil to form a first and partially second bend; rotating said knotting pinion to wind said tail about said adjacent coil winding for at least one-half turn; moving said knotting pinion away from said coil thereby to bend said winding in a direction 45 away from the center of said coil, thereby to complete said second bend and form said end coil into a circular configuration; further winding said tail about said adjacent coil winding for a total of approximately two and a half turns; and bending said coil close to said turns in a direction toward the base of said coil, thereby to form a third bend to secure said turns and to form said lock knot.

2. A method of forming a lock knot on a coil spring by means of a knotting pinion and means to control same 55 and comprising the steps of: securing said coil spring at one end thereof and leaving the tail free; bending a tail end of said coil spring in towards the center of said coil until said tail is substantially at right angles to the adjacent coil winding; moving said knotting pinion into position about said adjacent winding, thereby to bend said winding backwards toward the base of said coil to form a first bend; winding said tail about said adjacent coil winding for at least one-half turn; moving said knotting pinion away from said adjacent winding thereby to bend said 60 winding in a direction away from the center of said coil, thereby to form a second bend; further rotating said knotting pinion to wind said tail about said adjacent coil winding first in an open manner and then in a closed manner, thereby to form a compressed coil of approximately two and a half turns; and bending said adjacent winding close to said turns in a direction toward the base of said coil, thereby to form a third bend to secure said turns and to form said lock knot.

3. A method of forming a lock knot on a coil spring 75 by means of a knotting pinion and means to control same

and comprising the steps of: securing said coil spring at one end thereof and leaving the tail free; bending a tail end of said coil spring in towards the center of said coil until said tail is substantially at right angles to the adjacent coil winding; moving said knotting pinion into position about said adjacent winding, thereby to bend said winding backwards toward the base of said coil to form a first bend; rotating said knotting pinion to wind said tail about said adjacent coil winding for at least one-half turn; moving said knotting pinion away from said adjacent winding thereby to bend said winding in a direction away from the center of said coil, thereby to form a second bend; further winding said tail about said adjacent coil winding first in an open manner and then in a closed manner, thereby to form a compressed coil of approximately two and a half turns; and striking said adjacent winding close to said turns in a direction toward said coil base, thereby to form a third bend and to hold said compressed coil in position.

4. A method of forming a lock knot on a coil spring by means of a knotting pinion and means to control same and comprising the steps of: securing said coil spring at one end thereof and leaving a tail end thereof free; bending the tail of the coil in towards the center of said coil until said tail is substantially at right angles to the adjacent coil winding; moving said knotting pinion into position about said adjacent winding, thereby to bend said winding backwards toward the base of said coil to form a first bend; rotating said knotting pinion to wind said tail about said adjacent coil winding for at least one-half turn; moving said knotting pinion away from said adjacent winding thereby to bend said winding in a direction away from the center of said coil, thereby to form a second bend; further winding said tail about said adjacent coil winding in an open manner to form a total of approxi-

mately two and a half turns; compressing said turns; and striking said adjacent winding close to said turns in a direction toward said coil base, thereby to form a third bend and to hold said compressed coil in position.

5. A method of forming a lock knot on a coil spring by means of a knotting pinion, said pinion having a radial slit extending from the center to the peripheral edge thereof, and means to control same, and comprising the steps of securing said coil spring at one end thereof, and leaving the tail free; bending said tail of the coil inwards towards the center of said coil until said tail is substantially at right angles to the adjacent coil winding, moving said knotting pinion with said radial slit at a slight angle to the plane of said coil spring into position about said adjacent winding, by rotating said knotting pinion, winding said tail about said adjacent coil winding, for half a turn, moving said knotting pinion in a direction away from the center of the coil, thereby forming a bend of the said adjacent coil winding, rotating said knotting pinion further, thereby winding said tail around said coil winding for two and one-half turns forming said lock knot, bending said adjacent coil close to said winding thereby to secure said lock knot in place, and striking said lock knot toward said coil base thereby to compress said lock knot to hold it in place.
